Inventor
Frederick Lather.

UNITED STATES PATENT OFFICE.

FRED LATHER, OF RIDGEVILLE CORNERS, OHIO.

HAME-TUG.

SPECIFICATION forming part of Letters Patent No. 427,092, dated May 6, 1890.

Application filed December 20, 1889. Serial No. 334,408. (No model.)

To all whom it may concern:

Be it known that I, FRED LATHER, a citizen of the United States, residing at Ridgeville Corners, in the county of Henry and State of Ohio, have invented a new and useful Hame-Tug, of which the following is a specification.

The invention relates to improvements in hame-tugs.

10 The object of the present invention is to provide a flexible hame-tug of simple and inexpensive construction, in which the sections may be readily separated and be quickly replaced when they have been worn or injured 15 by long use.

The invention consists in the construction and novel combination and arrangement of parts hereinafter fully described, illustrated in the accompanying drawings, and pointed 20 out in the claims hereto appended.

In the drawings, Figure 1 is a perspective view of a hame-tug constructed in accordance with the invention. Fig. 2 is a longitudinal sectional view. Fig. 3 is a detail view 25 of the loop that connects the sections and renders them adjustable. Fig. 4 is a similar view of the eye by means of which the tug is attached to a hame.

Referring to the accompanying drawings, 30 1 designates a section of a flexible hame-tug composed of layers of leather doubled upon themselves to provide an eye at its rear end to receive a removable pin 2 of a loop 3, that connects the section 1 to a section 4 and renders the sections adjustable, and enables 35 them to successfully withstand strain at the point where a hame-tug is most liable to break.

The section 1 of the hame-tug is designed 40 to be connected to a hame by a loop 5, whose ends terminate in parallel plates 6, that are perforated and riveted to the section 1, one of the plates lying upon the outer face of the section and the other being inserted between 45 the layers of leather forming the section. The removable bolt of the loop 3 is provided 50 with a sleeve 7, that acts as an anti-friction roller and prevents the eye of the section 1, through which the bolt passes, becoming worn and broken, and the said bolt has its end

threaded and is passed through perforations 8 in the end of the arms of the loop 3, one of the perforations 8 being threaded to engage the threaded end of the bolt. The section 4 is composed of layers of straps, which are 55 doubled and form eyes 9 and 10, located, respectively, at the front and rear of the section, the latter to receive a buckle 11 to afford means for securing the trace and the former to receive the cross-bar 12 of the loop 3, 60 which cross-bar may, if desired, be provided with a sleeve or anti-friction roller similar to the removable bolt.

It will thus be seen that the hame-tug is 65 flexible and simple and inexpensive in its construction, and is capable of successfully withstanding the strain at a point where hame-tugs of the ordinary construction are most liable to break.

Having thus described my invention, what I 70 claim, and desire to secure by Letters Patent, is—

1. A hame-tug comprising the sections 1 and 4, provided with eyes at their adjacent ends, and the loop secured in the eye of one 75 of the sections and provided with a removable bolt engaging the eye of the other section and having a sleeve, substantially as and for the purpose described.

2. A hame-tug comprising the section 1, 80 provided at its rear end with an eye, the loop 5, provided with parallel plates and secured in the front of said section, the section 4, having an eye at its front end, and the loop 3, having its cross-bar 12, arranged in the eye 85 of the section 4 and being provided with a removable bolt engaging the eye of the section 1, and provided with a sleeve and engaging the eye in the section 1, substantially as and for the purpose described. 90

In testimony that I claim the foregoing as my own I have hereto affixed my signature in presence of two witnesses.

FRED ^{his} LATHER.
